US00D909339S

(12) **United States Design Patent** (10) Patent No.: **US D909,339 S**
Boyd et al. (45) Date of Patent: ** Feb. 2, 2021

(54) **SPEAKER**

(71) Applicant: **Apple Inc.**, Cupertino, CA (US)

(72) Inventors: **Robert Boyd**, Los Angeles, CA (US);
Eric D. Fields, San Francisco, CA (US); **Christopher Kuh**, San Francisco, CA (US); **Robert D. Brunner**, San Francisco, CA (US); **Monica Fernandez**, Reseda, CA (US)

(73) Assignee: **Apple Inc.**, Cupertino, CA (US)

(**) Term: **15 Years**

(21) Appl. No.: **29/702,844**

(22) Filed: **Aug. 22, 2019**

Related U.S. Application Data

(63) Continuation of application No. 29/617,447, filed on Sep. 14, 2017, now Pat. No. Des. 857,660, which is a continuation of application No. 29/541,135, filed on Sep. 30, 2015, now Pat. No. Des. 797,703.

CLAIM

(57) The ornamental design for a speaker, as shown and described.

DESCRIPTION

FIG. 1 is a top front perspective view of a speaker showing the claimed design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures show portions of the speaker that form no part of the claimed design.

1 Claim, 7 Drawing Sheets
